UNITED STATES PATENT OFFICE.

IRWIN B. SIMON, OF SAN FRANCISCO, CALIFORNIA.

DESIGN FOR A HAT.

Application filed April 19, 1928. Serial No. 26,384 Term of patent 3½ years.

To all whom it may concern:

Be it known that I, IRWIN B. SIMON, a citizen of the United States, and a resident of the city and county of San Francisco, State of California, have invented a new, original, and ornamental Design for a Hat, of which the following is a specification, reference being had to the accompanying drawing, forming part thereof, and in which—

I claim:

The ornamental design for a hat, as shown.

IRWIN B. SIMON.
